UNITED STATES PATENT OFFICE

JOSEPH MARTIN SCHUTZ, OF MINNEAPOLIS, MINNESOTA.

ROLLER-MILL.

SPECIFICATION forming part of Letters Patent No. 363,687, dated May 24, 1887.

Application filed December 11, 1885. Renewed January 23, 1887. Serial No. 225,784. (No model.)

To all whom it may concern:

Be it known that I, JOSEPH MARTIN SCHUTZ, a citizen of the United States, and a resident of Minneapolis, in the county of Hennepin and 5 State of Minnesota, have invented certain new and useful Improvements in Roller-Mills, of which the following is a specification.

Figure 1 is a sectional side elevation on line $x x$ of Fig. 2. Fig. 2 is a sectional front elevation on the line $y y$ of Fig. 1; Fig. 3, a side elevation of the machine on the adjustment side. Fig. 4 represents detached views, in perspective, illustrating the construction of the supports for the lower chute and the con- 15 veyer-trough. Fig. 5 represents one of the adjustment-levers detached. Fig. 6 represents one of the cams detached and in perspective, whereby the alignment of the rolls is pre- 20 served. Fig. 7 represents the adjustment-lever cam mechanism, detached and in perspective, whereby the distance between the rolls is regulated.

$A' A^2$ are the side frames, between which the rolls are journaled, connected together by the 25 tie beams or bolts a in the ordinary manner.

$B' B^2 B^3$ are three grinding-rolls, placed in line perpendicularly between the sides $A' A^2$, and with their journals $b' b^2 b^3$ passing out through the said sides, as shown. The center roll is 30 held in a fixed relation to the frame $A' A^2$ by being journaled in bearings $c' c^2$ on the frame, while the upper and lower rolls are made adjustable with relation to the center roll by means of levers $D' D^2$, in which their journals 35 $b' b^3$ are arranged to be held by caps $d' d^2$, as shown in Figs. 3 and 5.

Projecting outward from the side frames, $A' A^2$, a short distance above and below and to one side of the points where the journals 40 $b' b^3$ pass through the side frames, are lugs $c^3 c^4$, through which bolts $c^5 c^6$ are passed from the inside outward, each bolt having a square head, c^6 , fitting into corresponding cavities in the side frames, so that the bolts can neither 45 be revolved nor pulled outward. Fitted loosely upon these bolts $c^5 c^6$, outside the lugs $c^3 c^4$, are small hexagonal or square collars c^1 , and to the inner sides of these collars are 50 formed small circular disks c^1 , which fit into corresponding circular cavities in the short ends of the levers $D' D^2$.

The holes through the disks c^1 and collars c^1 ,

in which the bolts $c^5 c^6$ fit, are off to one side of the center a short distance to form the disks into eccentrics, so that by revolving them in 55 the levers the latter may be adjusted to the right or left, and thereby adjust the rolls $B' B^3$ laterally to insure their perfectly parallel position axially or in true line perpendicularly. This is a very important feature of my invention, as it enables me to adjust the upper and lower rolls laterally, and thus cause them to 60 run perfectly true and in line with the center roll.

Holding-nuts c^{13} will be placed on the outer 65 ends of the bolts $c^5 c^6$ to clamp the collars c^1 and eccentrics c^1 fast to the lugs $c^3 c^4$, and thus hold the eccentrics fixed in the levers $D' D^2$, and hold the latter firmly whenever desired.

Each end of each of the rolls $B' B^3$ will be 70 provided with a set of these levers and their adjusting mechanism.

The opposite or long ends of the levers $D' D^2$ are held by rods $E' E^2$, the lower ends of the former and the upper ends of the latter 75 being secured to the central parts of the side frames, $A' A^2$, by cams $e' e^2$, fitting over the ends of a shaft, e^3 , passing through both the side frames, $A' A^2$. Beneath the levers D' and above the levers D^2 the rods $E' E^2$ are 80 provided with jam-nuts $g' g^2$, by which the levers may be adjusted with relation to the rods. Above the levers D' and beneath the levers D^2 coiled springs $F' F^2$ are arranged around the rods $E' E^2$, and held in place and adjusted by 85 nuts $g^3 g^4$, as shown. By this arrangement the long ends of the levers are supported in the direction of their greatest strains by the springs $F' F^2$, which are strong enough to resist the pressure of the ordinary material which passes 90 between the rolls, but will be compressed and allow the rolls to be spread apart in event of any foreign hard matter getting in between the rolls, and thereby prevent injury to the rolls.

The eccentrics or cams $e' e^2$ are fast upon the shaft e^3 , and the latter is provided with a hand-lever, e^4 , by which it may be oscillated. This lever is provided with a slotted segment, e^5 , by which the lever may be clamped in any position by a thumb-screw, e^6 , connected to the frame A' . By this means the eccentrics $e' e^2$ may both be turned at once by the lever e^4 and raise and lower the long arms of the levers D' 95

D², and thus set the rolls B' B³ nearer to or farther away from each other.

After the rolls have been once adjusted by the jam-nuts g' g², the rolls may be adjusted very quickly for coarse or fine grinding by simply moving the lever e⁴ to some designated mark on the segment e⁵, so that as long as the adjustment by the nuts g' g² remains true the change of the grade of the rolls may be accomplished entirely by the lever e⁴. By these two adjustments—viz., laterally by the eccentrics c', and vertically by the nuts g' g² and cams e' e²—I am enabled to very quickly and easily adjust the rolls to run perfectly true both laterally and vertically.

G' is a feed-hopper, into which the material to be fed through the rolls is placed. The bottom of this feed-hopper is formed of a plate, G², supported by spring-arms, G³ G⁴ from the sides A' A², and inclining downward away from the center of the hopper on both sides, as shown, and adapted to be vibrated by cams h' on a cross shaft, h², the cams running between uprights h³ on the plate G². This shaft h² is adapted to be revolved very rapidly (about six hundred revolutions per minute) by a belt, h⁴, leading from a pulley, h⁵, on the shaft b³ of the lower roller, B³, upward over a pulley, h⁶, on the shaft h², and thus cause it to vibrate the plate G² and cause the material to be fed off over its edges in thin even streams to the rollers below.

G⁵ G⁶ represent feed-doors adapted to be adjusted higher and lower by screws G⁷ G⁸, to open and close the spaces between the hopper G' and the edges of the vibrating plate G², to regulate the feed.

H' is a chute fixed across between the sides A' A² and adapted to guide the material. From one side of the hopper G', between the rolls B' B² and H', is a similar chute, arranged to guide the material which falls from the other side of the hopper between the rolls B² B³, as shown.

K' is a screw-conveyer journaled by bearings k² k³ in the sides A' A², opposite the center roll, B², and running in a trough, k⁴, as shown. The side of this trough k⁴ next the roll B² is bent off at an angle and adapted to rest against the roll, and thus serve as a scraper to cause the material passing between the rolls B' B² to all run into the conveyer.

The conveyer K' is formed right and left handed, so that the material will be equally divided and carried off to each side.

The ends of the trough k⁴ rest upon ribs on angular-shaped plates M' M², the latter embedded into the wooden linings L' L² of the side A' A². One of these plates, M², is shown in perspective in Fig. 4. The lower edges of the plates M' M² are inclined to correspond to the chute H', and are provided with ribs i, on which the chute is supported. Behind these plates M' M² the linings L' L² are pierced with slots or cavities, and opposite these cavities the side frames, A' A², are formed with hoods M³ M⁴, forming pockets M⁵ M⁶. The ends of

the conveyer K' open into the upper ends of these pockets, and the lower ends of the pockets open into the interior of the machine beneath the plates M' M². The material from the conveyer K' is thus carried around the chute H', while the material passing over the latter runs beneath the trough k⁴ and between the rollers B² B³. By this means two separate grindings are obtained with only three rolls, B' B² B³.

Small doors M⁷ M⁸ are formed in the hoods M³ M⁴, opening outward in the line of the path of the ground material, to form a means of escape for the material from the conveyer K' should it become clogged in the pockets. This is a very important feature of my invention, as, without some such device, any clogging that might occur would cause the material to "back up" between the rolls B' B² or become packed into the conveyer. The ordinary flow of the material will not affect these small relief-doors M⁷ M⁸, which are heavy enough to resist it, but are only operative in event of the clogging of the lower parts of the pockets M⁵ M⁶.

The front A³ and back A⁴ of the frame of the machine, as shown in Fig. 1, are formed with removable doors A⁵ A⁶, so that the interior of the machine may be inspected; and the chutes H' H² are removable for the same purpose.

The chutes H' H² are provided with cams m, by which they are held in place on the ribs i, as shown in Figs. 1 and 4.

H³ is a third chute, resting by its lower edge on the upper outer edge of the trough k⁴ of the conveyer K' and projecting upward beneath the vibrating feed-plate G², to prevent the material falling from the feed-plate passing into the conveyer, but guiding it all upon the chute H'. The conveyer is shown as driven by gears K⁶ K⁷ from the shaft b² of the center roll, B².

N' is an idler-pulley resting against the belt h⁴ and journaled on one end of a hanger, N², the other end of the latter being pivoted to the pin or bolt c⁶ of the adjusting-lever D², or to some other fixed part of the frame, and connected near its upper end by a rod, N³, to the segment e⁵ of the lever e⁴, as shown. The belt h⁴ is loose enough so that when the idler N' is removed from contact with it the belt will not act upon the pulley h⁵; hence when the lever e⁴ is turned to throw the rolls B' B² B³ out of operation the same action, by means of the rod N³, connecting the lever e⁴ and idler-hanger N², will remove the idler from contact with the belt h⁴, and thus at once stop the motion of the feed-plate G², so that the feeding of material will cease at the same time that the rolls are thrown out of operation. By this means no waste of material occurs, as the feed-plate is so flat that the material will not flow over it unless it is vibrated.

It may be found necessary or advantageous under some circumstances to move the upper and lower rollers, B' B³, laterally, instead of perpendicularly, which may be done by the

cams c^7 , there being nothing in the construction of the mechanism to prevent this.

Having thus described my invention, what I claim as new is—

5. 1. In a roller-mill, a center roll, B^2 , mounted in fixed bearings, fixed bolts $c^5 c^6$, circular disks $c^1 c^5$, eccentrically mounted on said bolts, and levers $D' D^2$, above and below said center roll, having circular cavities or apertures which fit 10 over said disks, in combination with rolls $B' B^3$, mounted on said levers above and below said center roll and in the same vertical line therewith, and mechanism which simultaneously moves the free ends of said upper and 15 lower levers in opposite directions, substantially as set forth.
2. In a roller-mill, a center roll, B^2 , mounted in fixed bearings, fixed bolts $c^5 c^6$, circular disks $c^1 c^7$, eccentrically mounted on said bolts, 20 nuts $c^{12} c^{13}$, by which said disks are clamped, and levers $D' D^2$, above and below said center roll, having circular cavities or apertures which fit over said disks, in combination with rolls $B' B^3$, mounted on said levers above and 25 below said center roll, and in the same vertical plane therewith, and mechanism which simultaneously moves the free ends of said levers in opposite directions, substantially as set forth.
3. In a roller-mill, a center roll, B^2 , mounted in fixed bearings, fixed bolts $c^5 c^6$, fixed lugs or sleeves $c^3 c^4$, in which said bolts are held, circular disks $c^1 c^5$, eccentrically mounted on said bolts, collars $c^{11} c^{12}$, formed on said disks, 35 and nuts $c^{13} c^{14}$ on said bolts, which clamp said collars against said lugs, whereby said disks are held in position, in combination with levers $D' D^2$, above and below said center roll, having circular cavities or apertures which fit 40 over said eccentric disks, rolls $B' B^3$, mounted on said levers above and below said center roll, and mechanism which simultaneously moves the free ends of said levers in opposite directions, substantially as set forth.
4. In a roller-mill, side frames, three rolls, 45 one above the other, chutes which convey material to be ground to said rolls, a trough located above and to one side of the lower rolls, to receive the material ground by the upper rolls, and a right and left conveyer running in 50 said trough, which conveys the ground material in opposite directions, in combination with projecting hoods $M^3 M^4$ on said side frames, opposite the ends of said conveyer, and relief doors $M^1 M^2$ in said hoods, which open in the 55 line of the path of the ground material, substantially as set forth.
5. In a roller-mill, side frames and three rolls, one above the other, mounted therein, in combination with chutes $H' H^2$, right and 60 left conveyer K' , trough k^4 , hoods $M^3 M^4$ on the side frames, opposite the ends of said conveyer, angular plates $M' M^2$, supporting said chute H^2 and trough k^4 , and cams m , for securing said chutes, substantially as set forth. 65
6. A roller-mill comprising side frames, A^2 , fixed roll B^2 , and adjustable rolls $B' B^3$, pivoted levers $D' D^2$, supporting said adjustable rolls $B' B^3$, rods $E' E^2$, shaft e^3 , provided with eccentric collars $e^1 e^2$ and lever e^4 , feed- 70 plate G^2 , shaft h^2 , having cams h' , pulley h^6 on said shaft, pulley h^5 on the shaft b^3 of said roller B^3 , belt h^4 , running over said pulleys h^5 h^6 , pivoted hanger N^2 , having idler-pulley N' , and rod N^3 , connecting said hanger with said lever e^4 , whereby the movement which separates the rolls $B' B^3$ from the roll B^2 also removes the idler from the belt h^4 , and thus stops the motion of said feed-plate, substantially as 75 set forth. 80

In testimony whereof I have hereunto set my hand in the presence of two subscribing witnesses.

JOSEPH MARTIN SCHUTZ.
